UNITED STATES PATENT OFFICE.

CASIN W. OBERT, OF BROOKLYN, NEW YORK.

AUTOMOBILE ATTACHMENT.

1,269,844.

Specification of Letters Patent. Patented June 18, 1918.

Application filed May 1, 1915. Serial No. 25,330.

To all whom it may concern:

Be it known that I, CASIN W. OBERT, a citizen of the United States of America, and resident of the borough of Brooklyn, in the county of Kings and State of New York, have invented certain new and useful Improvements in Automobile Attachments, of which the following is a specification.

This invention relates to improvements in and relating to automobile attachments, and particularly an improved timer-elevator and supplementary oil-filler, to be placed on such automobiles of fixed construction as the Ford. In such cars as at present constructed and placed on the market, the timer is placed in such position with respect to the engine that it is not easily and quickly accessible, being located at the base of the crank case behind the radiator, where oil is very often spattered over it and the wires leading from it (causing troublesome short-circuits), and the timer is repaired and cleaned with great difficulty. Where timer-elevators, or timer-brackets (so called) are applied to remedy these troubles, it has been found impossible to so arrange them as not to interfere with the oil-filling device on the crank case, and in such combination, it is difficult or impossible to fill the crank case with oil without wasting of the oil on the engine and car.

It is an object of the present invention, therefore, to provide such an improved combined supplementary oil-filler and timer-bracket, that both the oil-filler and timer are in a conveniently accessible position, so that the engine may be oiled, even in the dark, with ease and without danger of the oil running over and spattering, and the timer may easily and quickly be repaired and cleaned. A further object is to provide such a device which is simple and economical in construction, and which can be quickly and securely attached to the above type of car.

With these and other objects in view, my invention comprises the novel features, arrangement and combination of parts, hereinafter more fully described with reference to the accompanying drawings, and particularly pointed out in the claims.

In the drawings,

Figure 1 is a view in elevation of my invention applied to an internal combustion engine;

Fig. 2 is an enlarged detail view thereof;

Fig. 3 is a view in elevation of a slightly modified form of construction; and

Fig. 4 is a view in elevation of a still further modified form of construction. 60

Similar reference characters indicate corresponding parts throughout the several views.

Referring to the drawings, and more particularly to Fig. 1 thereof; an internal combustion engine 10 is provided for a front cover plate 11 of the crank case, on which is arranged an oil-filler 12, and the bevel gears 13 and 14 connected to the cam shaft for actuating the timer, as is well known. 70 In the present construction of this type of engine, the timer, is supported on the gear casing 18 shown in Fig. 1, which casing is attached to the cover plate by means of nuts and bolts 16 passing through extensions 19 and 20. With this construction the oil-filler is made inconvenient of access, and it is an object of the present invention, therefore, to provide means whereby an extension or supplementary oil-filler may be provided 80 on the present oil-filler. For this purpose, the gear casing 18 has, in one embodiment of my invention, projecting upwardly therefrom and cast integral therewith a supporting member 22, which terminates in a hollow 85 oil-filling extension or supplementary oil-filler 23 extending outwardly and upwardly therefrom and provided with a hinged cap 24, and a downwardly projecting flange 39 adapted to rest in the oil-filler 12. A projection 25 is also provided at the upper end 90 of the supporting member 22, cast integral therewith, and provided with a hole 26 extending therethrough and in alignment with the bevel gear 14. A shoulder 27 is provided on the projection 25, and the timer 28 is supported thereon, which is actuated by means of a shaft 29 extending through the opening 26, and secured to the said bevel gear 14. It will be seen that with this construction a very conveniently placed oil-filler is provided, and by means of the bracket, the timer is supported in an easily accessible position. 95

In the form of construction shown in Fig. 3, a supplementary oil-filler 30 is provided having a hinged cap 31 and a downwardly-extending flange 32 adapted to fit within the oil-filler 12, and having lugs or ears 33 which are secured to the oil-filler by 110 means of a bolt passing through a hole thereof. A projection 34 is provided on the

supplementary oil-filler, cast integral therewith, and provided with an opening 35 extending therethrough, and in alinement with the gear 14. This projection serves as a 5 bracket for the timer 28 and shoulder 27, which are supported thereon and connected to the gear 14 by means of the shaft 29 extending through the opening 35 in a manner similar to that described with reference to

10 Fig. 1.

In the form shown in Fig. 4, the construction is similar to that shown in Figs. 1 and 2, with the exception that the supplementary oil-filler is not made integral with the timer-elevator bracket, but is made to swivel so as to be readily accessible. A ring 36 is provided at one side, integral with the projection 25, and is adapted to support the supplementary oil-filler 37 over the oil-filler 12. 15 The supplementary oil-filler 37 is provided with a downwardly projecting flange 38, which is adapted to be fitted into the oil-filler 12, and adapted to be engaged by screws 39 engaging a groove 40 therein, to 20 permit the supplementary oil-filler to be swiveled, but such as to prevent the oil-filler to be removed, without removing the screws.

It will thus be seen that the supplementary oil-filler provides convenient access for 25 filling it with oil and for otherwise manipulating it, and at the same time is suitably held in position by the elevated timer-bracket. By offsetting the oil-filler, the timer-bracket may be constructed in the 30 most advantageous form. Hitherto, it was necessary to build the timer-bracket quite high to enable the oil-filler to be manipulated. The offset feature of the supplementary oil-filler enables the filling to take 35 place, without building the timer-bracket as high as heretofore. By the improved combined timer and oil-filler bracket, a very compact structure results, with special advantages attendant such combination. By 40 the swiveling of the supplementary oil-filler, the additional advantages are obtained in

that while the funnel may be brought into convenient filling position at will, it may also be swiveled around to one side so as not to interfere with the access to the valve 50 mechanism of the motor, to which free access is desirable in grinding valves.

I have illustrated preferred and satisfactory forms of my invention, but it is obvious that changes may be made therein within the spirit and scope thereof, as defined in the appended claims.

I claim:

1. In a device of the character described the combination of a motor casing, a gear 50 casing supported in the motor casing and having an upwardly extending duplex bracket forked in opposite directions, an elevated timer supported at its lower part by said gear casing and in its upper part by 55 one branch of said fork, and an elevated offset oil filler connected with the other branch of said fork.

2. A device of the character described comprising a gear casing having an upward 70 extension provided with a lateral projection constituting an elevated timer support and a lateral projection constituting a supplemental oil filler support; and a supplemental oil filler adapted to turn in said oil filler 75 support.

3. A device of the character described comprising a gear casing having an upward extension provided with a lateral projection constituting an elevated timer support and 80 a lateral projection constituting a supplemental oil filler support, and an offset supplemental oil filler having a curved neck adapted to turn in said oil filler support.

In testimony that I claim the foregoing 85 as my invention, I have signed my name in presence of two subscribing witnesses.

CASIN W. OBERT.
